UNITED STATES PATENT OFFICE.

CHRISTIAN H. GOEBEL, OF PHILADELPHIA, PA., ASSIGNOR TO THE AMERICAN SECTIONAL ELECTRIC UNDERGROUND COMPANY, OF NEW JERSEY.

CONDUIT FOR ELECTRIC WIRES.

SPECIFICATION forming part of Letters Patent No. 290,413, dated December 18, 1883.

Application filed July 26, 1882. (No model.)

To all whom it may concern:

Be it known that I, CHRISTIAN H. GOEBEL, a citizen of the United States, residing in the city and county of Philadelphia, State of Pennsylvania, have invented a new and useful Improvement in Underground Conduits for Electric Wires, which improvement is fully set forth in the following specification and accompanying drawings, in which—

10 Figure 1 is a top or plan view of the conduit embodying my invention. Fig. 2 is a transverse vertical section thereof.

Similar letters of reference indicate corresponding parts in both figures.

15 My invention consists of a conduit constituting a curb, gutter, and portion of a street, each member of which is removable without disturbing the other members, and may be opened at top, in order that its interior may

20 be conveniently accessible for laying, repairing, inspecting, testing, and removing the wires.

Referring to the drawings, A represents a conduit formed of tubes *a b c*, the tube *a* occupying the position of a curb of a street or roadway, the tube *b* that of a gutter, and the tube *c* that of the portion of the street adjacent to the gutter, each tube being disconnected from the other, so that the conduit may be

25 readily laid, and either tube removed and reapplied without disturbing the remaining tubes, each tube, moreover, having a lid or cover, *d*, so that access is readily had to the interior thereof for the purpose of laying, re-

30 pairing, inspecting, testing, and removing the wires. On the sides of the tubes are hooks *e*, which are cast with or secured to the tubes,

and support the electric wires or cables, as clearly shown in Fig. 2. The tube *a* is in cross-section of the form of a right-angled triangle, the base being above and the perpendicular on the outside or curb line, so that as the hypotenuse comes next to the ground the tube acts as a wedge, which, when driven into position, tightens the tubes one against the other, and compresses the earth of the sidewalk, thus producing a firm and compact support for the tube *a*, it being evident that the tube *c* may also be wedge-shaped, so as to compress the earth of the street. Each tube is 40 provided on the inner faces of its sides with supports *e*, which keep the individual wires 45 separate.

In practice I prefer to use one tube for electric-light wires, one for telephone-wires, and 50 one for telegraph-wires.

Having thus described my invention, what I claim as new, and desire to secure by Letters Patent, is—

1. The wedge-shaped tube *a*, in combination with tube *b*, which it bears against, whereby said tube *a* is caused to compress the earth at its side and tighten the tubes together. 60

2. The wedge-shaped tube *a*, in combination with tube *b*, which it bears against, and tube *c* on the other side of tube *b*, the three tubes forming a curb, gutter, and part of a street, and the pressure of tube *a* against tube *b* serving to compress the earth and tighten the tubes together, substantially as set forth. 65 70

CHRISTIAN H. GOEBEL.
